DESCRIPTION

U.S. PATENT DOCUMENTS

FIG. 1 is a perspective view of the flexible bathtub waste pipe assembly showing the new design;

437,289 A	9/1890	Clark	
1,018,021 A *	2/1912	Willets	4/679
1,068,039 A *	7/1913	Clark	285/191
1,213,466 A	1/1917	Delanoy	
1,692,710 A	11/1928	Spanh	
1,781,719 A *	11/1930	Darling	4/683
1,873,274 A	8/1932	Boosey	
1,925,008 A	8/1933	Schact	
1,980,493 A	11/1934	Morrisseau	
2,044,253 A	6/1936	Morris	
2,084,437 A *	6/1937	Frankenberger	4/694
2,580,575 A	5/1949	Muckler	
3,263,244 A *	8/1966	Katz	4/252.4
3,416,982 A	12/1968	Petzetakis	

FIG. 2 is a front elevation view thereof, the rear elevation view being a mirror image of the front elevation view;

FIG. 3 is a perspective view of an alternate embodiment of the flexible bathtub waste pipe assembly, the only difference being the omission of portions associated with the elbows shown; and,

FIG. 4 is a front elevation view thereof, the rear elevation view being a mirror image of the front elevation view.

The broken lines in the figures show environment and is for illustrative purposes only and forms no part of the claimed design.
